UNITED STATES PATENT OFFICE.

FRED R. ALLEN, OF PROVIDENCE, RHODE ISLAND, ASSIGNOR, BY MESNE ASSIGNMENTS, TO NATIONAL ENVELOPE SEALING AND STAMPING MANUFACTURING COMPANY, A CORPORATION OF MASSACHUSETTS.

MOISTENER.

1,059,336.

Specification of Letters Patent.

Patented Apr. 22, 1913.

Application filed June 24, 1911. Serial No. 635,241.

To all whom it may concern:

Be it known that I, FRED R. ALLEN, a citizen of the United States, residing at the city of Providence, in the county of Providence and State of Rhode Island, have invented certain new and useful Improvements in Moisteners, of which the following is a specification, reference being had therein to the accompanying drawing.

10 This invention relates to a moistening device for envelopes, labels, or other matter, and has for its object to provide a moistener of this character having a wick communicating directly with the moisture supplying reservoir the free end of said wick being pivotally mounted and arranged to extend into the path of movement of the material to be moistened, whereby the wick is adapted to automatically adjust itself to the 15 varying thicknesses of the passing material and supply a uniform quantity of liquid thereto.

With these and other objects in view, the invention consists of certain novel features 20 of construction, as will be more fully described and particularly pointed out in the appended claims.

In the accompanying drawings: Figure 1— is an elevation showing my improved 25 moistener attached to the table of a stamp affixing machine. Fig. 2— is a plan view showing the reservoir as attached to the table and having the wick extending laterally therefrom into the path of movement of the 30 matter to be moistened. Fig. 3— is a sectional elevation through the reservoir and wick tube on line 3—3 of Fig. 2.

Referring to the drawings, 1 designates the table over which the matter to be 35 moistened is fed, said table being illustrated herein as connected to a machine primarily adapted for affixing stamps to envelopes and other mail matter. 13 designates a narrow rib on one edge of the table for guiding the 40 envelop or other matter under the moistener and to the machine for subsequently operating upon the same.

The moisture supplying reservoir 2 may be made in any suitable form, but I have 45 herein shown the body portion 6 of the same as constructed substantially in the form of a barrel, the upper surface at one end being flattened as at 3 and adapted to be secured by screws 4—4, or other suitable means to

the table 1. The upper wall of this barrel is 50 provided with a slot or opening as at 5, see Figs. 2 and 3, at either end of which are upwardly projecting ears 7—7. Between these ears is pivotally hung a tube 8 which is offset laterally, see Fig. 2, so as to lead or 55 conduct the free end 9 of the wick 10 contained within it laterally and cause the same to extend over the table 1. The reservoir is provided with a filling opening 11 into 60 which is screwed a closed plug 12.

An essential feature of my invention is the construction whereby the wick passes through this tube 8 and through the opening 9 down into the reservoir, which reservoir is supported at one side of the path of 65 movement of the material to be moistened, while the delivery end of the tube and the wick is offset and led to a point directly above the path of movement of the matter to be moistened.

Owing to the fact that one end of the tube from which the wick protrudes is gravity 70 pressed and free to swing vertically, the wick will readily yield to permit the material no matter how thick, to pass beneath 75 and the amount of moisture deposited thereon will be practically uniform as the pressure due to gravity is always the same.

If in practice under some circumstances it is found advisable to increase the pressure of the wick upon the matter to be 80 moistened, a weight may be applied to the free end of the tube, or a spring 14 may be applied thereto for this purpose if desired.

I claim:

1. A moistener comprising a reservoir, a tube pivotally hung on said reservoir, a wick in said tube of substantially uniform width throughout its length and having one end communicating with said reservoir and its 90 opposite end extending into the path of movement of the material to be moistened whereby said wick may automatically adjust itself to the varying thicknesses of said passing material.

2. A moistener comprising a reservoir, an offset tube pivotally hung on said reservoir, a wick in said tube of substantially uniform width throughout its length and having one end communicating with said reservoir and its 100 opposite end following the offset portion of said tube and extending into the path of movement of the material to be moistened.

whereby said wick may automatically adjust itself to the varying thicknesses of said passing material.

3. In a moistening device, a table, a reservoir provided with an opening in its upper wall, an offset tube pivotally mounted to said reservoir above said opening, a wick in said tube of substantially uniform width throughout its length and having one end 10 extending through said opening into said reservoir the opposite end of said wick following the contour of said tube and extending over said table and into the path of movement of the material to be moistened, 15 whereby said wick may automatically adjust itself to the varying thicknesses of said passing material.

4. In a moistener, a table over which the material to be moistened is fed, a reservoir

having a slot in its upper wall, a laterally offset tube pivotally mounted on said reservoir and above said opening, a wick in said tube of substantially uniform width throughout its length and having one end extending through said slot into said reservoir the opposite end of said wick following the offset contours of said tube and extending out over said table and into the path of movement of the material to be moistened whereby said wick may automatically adjust itself to the 30 varying thicknesses of the passing material.

In testimony whereof I affix my signature in presence of two witnesses.

FRED R. ALLEN.
